UNITED STATES PATENT OFFICE

2,052,664

LUBRICATING APPARATUS

Lutwin C. Rotter, Glendale, Mo., assignor to Lincoln Engineering Company, St. Louis, Mo., a corporation of Missouri

Application December 29, 1930, Serial No. 505,243

19 Claims. (Cl. 184—7)

This invention relates to fluid pressure alternating and regulating means, and with regard to more specific features, to means for delivering a lubricant alternately to several conduits 5 at predetermined pressures.

Among the several objects of the invention may be noted the provision of improvements in the alternating and regulating portions of the lubricating system set forth in United States 10 Patent 1,805,303; the provision of an improvement in which is effected hydraulic operation instead of mechanical operation; the provision of apparatus of the class described which provides at least two cooperating alternators in 15 one unit; the provision of apparatus of the class described which provide alternators for alternating a working pressure, one of said alternators being operable by said working pressure, and the other being operable by a secondary pressure; the provision of apparatus of the class 20 described which provides regulators for cooperating with at least one of the alternators; and the provision of apparatus of the class described which is compact in structure and provided with 25 a means adapted to insure operability. Other objects will be in part obvious and in part pointed out hereinafter.

The invention accordingly comprises the elements and combinations of elements, features of 30 construction, and arrangements of parts which will be exemplified in the structure hereinafter described, and the scope of the application of which will be indicated in the following claims.

In the accompanying drawings, in which is 35 illustrated one of various possible embodiments of the invention,

Fig. 1 is a left side elevation of one form of a device embodying the invention;

Fig. 2 is a horizontal section taken on line 2—2 40 of Fig. 1;

Fig. 3 is a vertical section taken on lines 3—3 of Figs. 1 and 4;

Fig. 4 is a horizontal section taken on line 4—4 of Fig. 1; and

Fig. 5 is a diagrammatic flow chart showing the invention installed in a pressure lubricating system.

Similar reference characters indicate corresponding parts throughout the several views of 50 the drawings.

Referring to the system as a whole, in Fig. 5, index A illustrates a main valve means or alternator, adapted to alternate to outlet lines I and O from a supply line 301, a fluid at working 55 pressure. Across the lines I and O are placed

distributing or metering devices E. The supply line 301 is connected with a pump capable of engendering a suitable pressure in the line. The distributing device E is adapted to force measured charges of grease through its outlets 5 to bearings or the like. The main alternator A is provided with an exhaust outlet 41, and whichever of the lines I and O is not connected with the inlet supply line 301, is connected with the exhaust line 303. Thus at all times one of the 10 lines I and O is under a relatively high working pressure and the other is under a relatively low pressure. At B is shown a secondary valve means or alternator adapted to be operated by a relief pressure, as regulated by the regulators shown 15 at C, and also adapted to alternate the main pressure between certain portions of the main alternator A thereby effecting the operation of the alternator A. At D is shown a valve means adapted to operate at a higher pressure than 20 that at which the regulators C operate, and is operable only when the pressure in the supply line 301 builds up excessively due to the dead centering of the valves in the alternators A and B. 25

Referring now more particularly to the measuring distributor device E of Fig. 5, there is illustrated at numeral 201 a body portion having preferably, though not necessarily concentric bores 203, 205 and 207 which, respectively, are 30 provided with a main piston 209 and piston heads 211 and 213, of a valve stem 215. Thus provision is made for the piston 209, the piston heads 211 and 213, and the stem 215 to move freely within the bores 203, 205 and 207. 35

The cylinders 205 and 207 are provided with the inlets 217 and 219 respectively which are connected with the main pressure lines I and O. Outlets 221 and 223 leading to points to be lubricated or to be provided with fluid for other 40 purposes, are also provided, and are prevented from direct communication with the inlets by the piston heads 211 and 213. By-passes 225 and 227 are provided to connect the inlets 217 and 219 with the inner bore 203. The piston 45 heads are adapted to operate under a difference of pressure between the inlets, and are adapted to alternately cover and uncover opposing sets of by-passes and outlets, as shown.

A brief description of the operation of this 50 measuring and distributing device is as follows: (Dense stippling represents higher pressure and less dense stippling represents lower pressure of the fluid.)

In Fig. 5 the main piston 209 has just com- 55

pleted a stroke by which it has forced fluid out of the outlet 223. To accomplish this, the fluid pressure from the inlet 217 has first forced the heads 211 and 213 to the positions shown (Fig. 5), thereby opening the by-pass 225, and allowing the fluid pressure to force the main piston 209 into the position shown. By means hereinafter described, the inlet fluid pressure is now changed to inlet 219. This change of fluid pressure forces the heads 211 and 213 over, thereby covering or closing the by-pass 225 and the outlet 223 and uncovering or opening the by-pass 227 and the outlet 221. In this way the fluid pressure from inlet 219 is conducted to the main piston 209 which forces the fluid (previously received from inlet 217) out of outlet 221. Thus fluid is delivered by lines 221 and 223 to any desired points for any useful purpose. A more complete and detailed description of the construction and operation of this device is contained in the patent previously mentioned.

The device E is a separate unit herein, but the devices A, B, C and D are combined as a single mechanical unit shown in Figs. 1 to 4.

With the above preamble in mind and referring to Figs. 1 and 2, numeral 1 shows a body portion, having an inlet 3 connected with the pressure supply line 301. The body portion also has two outlets 5 and 7 connected with the working pressure lines I and O. The inlet 3, by means of a bore 9, is connected to the main alternating means which comprises in part a bore 13 in the body portion 1. The outlets 5 and 7 are connected to the bore 13 by bores 31 and 37 and 35 by bores 33 and 39 respectively. Bores as referred to herein are presumed to be any form of suitable passages or conduits, the term bores being used synonymously with conduit, opening or passage. The bore 13 serves to slidably accommodate a piston 17. The piston 17 has a peripheral depression 25 forming a movable connecting port between the inlet bore 9 and the outlet bores 37 and 39.

A bore 43 in the body portion 1 is connected to the exhaust outlet 41 which in turn is connected to the exhaust line 303. Bores 49 and 51 in the body portion connect the bore 13 with the exhaust bore 43. The piston 17 also has grooves 27 and 29 which serve to connect the bores 31 and 49 and 33 and 51, respectively, when the piston 17 assumes certain positions. Plugs 73 and 75, threadably positioned in the ends of the bore 13, serve to seal the ends of the bore and to provide means to limit the movement of the piston 17.

It will be seen that when the piston 17 is in the position as shown in Fig. 2, the pressure line 301 is connected to the main line O by way of the inlet 3, the bore 9, the port 25, and the bore 39 and the outlet 7. The bore 33 also connects the line O to a vertical bore 83. Also, when the piston 17 is in this position, the line I is in communication with the exhaust line 303 by way of the outlet 5, the bore 31, the groove 27, the bores 49, and 43 and the outlet 41. It is thus seen that when the outlet O is under working pressure, the outlet I is connected with the exhaust.

The secondary alternator in the body portion 1 comprises a bore 11 and a piston 15, said bore serving to slidably accommodate the piston 15. The bore 11 is connected with the bore 9 by the bore 12, and to the exhaust bore 43 by bores 45 and 47. Bore 11 is connected with one end 75 of the bore 13 by a bore 57, and bores 53. Like-

wise bore 59 connects the bore 11 with the opposite end of the piston 17 by way of the bore 55. Passages 95 and 97 are connected with the lines 53 and 55, respectively.

The piston 15 has a peripheral depression 23 5 constituting a movable connecting port between the inlet passage 9 and the respective bores 57 and 59. The piston also has grooves 19 and 21, serving to connect the bores 45 and 95, and the bores 47 and 97, when the piston assumes certain 10 limiting positions. Bushings 77 and 79 threaded in the ends of bore 11 provide means to limit the movement of the piston 15 and are adapted to threadably receive pipes 65 and 67 respectively.

It is clear that when the piston 15 is in the 15 position shown in Fig. 2 the pressure from the inlet 301 is transmitted to the left end of the piston 17, by way of the bores 57, 61 and 53. It is also seen that the opposite end of the piston 17 is connected to the exhaust line 303 by way 20 of the bores 55, 63, 97, by the groove 21 and the bore 47. It is also seen that the exhaust bore 45 is closed by the piston 15. Thus the pressure from the line 301 is being transferred to one end 25 of the piston 17, whereas the other end of the piston 17 is under the pressure existing in the exhaust line 303.

When the piston 15 assumes its right hand position at the right of the body 1, the passage 57 will be closed and the passage 45 opened, 30 thereby allowing the left hand end of the piston 17 to be connected with the exhaust line 303; whereas the right hand end of the piston 17 will be connected with the pressure line 301. Thus it is seen that when one end of the piston 17 is under pressure, the other end is connected with the exhaust.

The new position of the piston 17 closes the bore 39, and at the same time connects the line O with the exhaust line 303 by way of the bore 33, 40 the groove 29 and the bore 51. At the same time pressure from the line 301 is transmitted by way of the bore 9, the port 25, and the bore 37 to the line I. Thus it is seen that by shifting the position of the piston 17, the pressure from the line 45 301 is alternated between the lines I and O. Moreover it is seen that this alternating of the piston 17 is accomplished by the hydraulic action of the main fluid pressure difference existing between the lines 301 and 303. 50

Referring now more particularly to Fig. 3, there are shown at numerals 91 and 93 bores in the body portion 1. These bores are threaded to receive base portions 87 and 89 respectively of regulating means 101 and 103. The bores 91 and 93 also are connected respectively to the outlet bores 31 and 33. As is shown in Fig. 3, the base portions 87 and 89 are formed to accommodate plungers 105 and 107 in bores 83 and 85, respectively. Springs 109 and 111 react against 60 said plungers 105 and 107 respectively, said springs being backed by adjustable heads 113 and 115 respectively, adjustably threaded to said bodies 87 and 89. The plungers 105 and 107 are connected with the springs 109 and 111 by means of the rods 145 and 147 and the resilient sealing plugs 149 and 151, interposed between the plungers and rods. The sealing means prevents any grease from passing to the inside of the heads 70 113 and 115. Enlarged shoulders formed on the lower portions of the rods 145 and 147 serve to limit the downward movement of the rods, to provide a flat for the springs 109 and 111, and to accommodate a threaded bore to threadably 75

receive the upper portions of the rods 145 and 147.

Suitable grooves 117 and 119 are formed in the plungers 105 and 107 to provide respective communication between the ports 125 and 127, and 121 and 123, when said plungers are in their lowermost positions attained under the influence of the springs 109 and 111. The ports 125, 127, 121 and 123 communicate with the lines 305 and 307, respectively, which in turn are connected to lines 67 and 65, said last-named lines being the ones which carry the relief pressure to the ends of said piston 15. Radial passages or bores 139 and 143 are provided in the body portions 1 between the bodies 87 and 89 respectively and are connected by way of a V-shaped passage 141. The passage 139 is connected with the exhaust outlet 41 by way of a passage or bore 137 (see Figs. 1 and 4).

It is thus seen that when the pistons 105 and 107 are in their lowermost positions, the lines 305 and 307 respectively are in communication with the exhaust line 303. When the plunger 107 is in its lowermost position, the line 307 is connected with the exhaust line 303 by way of the bore 121, the groove 119 and the passages 123, 143, 141, 139, 137 and 43. In the same way when the plunger 105 is in its lowermost position the line 305 is connected with the exhaust line 303 by way of the bore 125, the groove 117 and the bores 127, 139, 137 and 43.

It will be seen, as shown in Figs. 5, 2 and 3, that when the plunger 107 is in its uppermost position, line O is placed in communication with the left end of the piston 15, this being done by way of the line 307. Hence by applying sufficient pressure to the underpart of the plunger 107 the pressure then existing in the line O is transmitted to the left-hand end of the piston 15. It is to be understood that the pressures at which the pistons 107 and 109 operate are higher than that which normally exists in the main pressure lines I and O. The lines 305 and 307 thus transmit pressures which are higher than the working pressure in the lines I and O, and these pressures are called for convenience relief pressures.

A description of the operation of the two alternators and the regulators, in the system as disclosed in Fig. 5 is as follows:

The line 301, as above stated, is connected with a grease pump capable of delivering grease under pressure. It is clear that the pressure in the line 301 is transmitted to the outlet 0 by way of the bore 9, the groove 25 and the bore 39. The line I is in communication with the exhaust 303 by way of the bore 31, groove 27, and the bores 49, 43 and 41. Thus there is effected in the lines O and I a working pressure difference, the line O being at this time at the higher pressure. Only exhaust, frictional pressure exists in the line I at this time.

The pressure in the line O causes the measuring distributor E to take up the location shown in Fig. 5. The heads 211 and 213 move from the other side of the device to the position shown in Fig. 5 under the influence of the working pressure difference in the lines O and I, thus closing off the inlet 219 from the line 223 and by-passing the material from the line O to a position behind the main piston 209, so that the main piston 209 at the working pressure forces the lubricant or the like from the main outlet 223 and to bearings or the like attached thereto. It will be seen that inasmuch as the line I is in communication with the exhaust line 303,

the movement of the valves 211 and 213 effects a recompression into said line I and a delivery of a small amount of grease into the exhaust line 303.

The distributor or ejector E has now attained the position shown in Fig. 5 by reason of the difference in pressures between the lines I and O. When the main piston 209 reaches the end of its stroke, the pressure in line O builds up beyond the working pressure, inasmuch as the pump supplying line 301 does not slow down. This increased pressure communicates itself to the underside of plunger 107 by way of the passages 33, 93. For convenience the passages 93, 85 and 33 are shown as 33 in Fig. 5. (Passage 15 31, Fig. 5, represents passages 31, 91 and 83.)

This pressure, communicated through the passage 33, results in lifting the plunger 107 to open the relief port 131 and to close the port 123, so as to permit the passage of this lubricant under relief pressure to one end of the piston 15; whereas the other end of said piston 15 does not receive this pressure but is connected by means of line 305, bore 125, groove 117 and bores 127, 139, 137 and 43, to the exhaust line 303. The passage 31 (in communication between the line I and the underside of the plunger 105 and with the exhaust 41) does not receive high enough pressure to lift the plunger 105. Thus there is effected a difference of pressure between the lines 305 and 307.

The pressure at which the plunger 107 will lift is adjustable by threading the cap 115 up or down on the body 89. Thus when it is found that the piston 209 of the distributor E is not being pushed completely over to supply a bearing in connection with the line 223, the cap 115 may be screwed down so that a higher pressure is required in the line O before the piston 15 will receive the pressure.

To continue the description of operation, it will be seen that under the pressure difference now existing in the lines 305 and 307, (Fig. 5), piston 15 will be thrown to the opposite end of its stroke. The opposite end of the piston 15 exhausts through the line 305, the passage 125, and through the passages 127, 139, 141, and 43 into the exhaust 303. This action of the piston 15 also closes the communication between the line 53 with the inlet 301, and opens a communication between the line 53 and the exhaust line 303 by way of the bore 95, groove 19, and bore 45. At the other end, the piston 15 closes communication between the line 55 and the exhaust line 303, and opens communication between the line 55 and the pressure line 301 by way of bore 9, the groove 23 and bore 59.

This reversal of the pressure difference in the lines 53 and 55, is communicated to the ends of the piston 17 inasmuch as the passages 53 and 55 are connected to the ends of the bore 13. This reversal or alternation in this pressure relationship forces the piston 17 to its left-hand position, the left-hand end of piston 17 exhausting by way of the line 53, the bore 95, groove 19 and the bore 45. This change of position of the piston 17 closes the communication between the inlet 301 and the outlet 0, and opens communication between the line O and the exhaust 303 by way of the bore 33, the groove 29, and the bores 51 and 43. Moreover the communication between the line I and the exhaust 303 is closed and the communication between the line I and the pressure line 301 by way of the bore 9, port 25, and the bore 37 is opened. The main pressure

is also transferred to the regulator 101 by way of the bore 31, (Fig. 5). The opening of the line O to the exhaust 303 permits the pressure in the line O to exhaust and hence the plunger 107 springs back into its lowermost position again connecting the line 307 with the exhaust 303. With the line I under pressure, and the line O under exhaust, the valve heads 211 and 213 are moved to their alternative positions, and the main piston 209 is forced to its other position, thereby forcing lubricant from the outlet 221. The pressure in the line I builds up as the piston 209 reaches the end of its stroke and this pressure is communicated to the under side of the plunger 105 by way of the passage 31. As before the plunger is pushed up when sufficient pressure develops in the passage 31 thereby cutting off the line 305 from the low pressure line 303, and transmitting the relief pressure to the line 305. This pressure communicated to the right-hand end of the piston 15, forces it to its left-hand position, the line 307 exhausting to the exhaust line 303. This change alternates the pressure in the lines 53 and 55 which results in throwing the piston 17 to its right-hand position, as shown in Fig. 5, the right-hand end of the piston 17 exhausting to the line 303 by way of the line 55. Thus the outlet O is again under pressure.

It is to be understood that the heads 113 and 115 can be independently adjusted to allow the plungers 105 and 107 to lift at the same or different pressures and thus the final pressure in the lines 221 and 223 may be independently determined before reversal takes place. Furthermore, the distributor or ejector E may supply fluid pressure bearings or the like and there may be any convenient number of ejectors in parallel in the lines I and O without disturbing the operation of the alternators A and B and the regulators C.

In Fig. 5 there is illustrated a safety device adapted to be included in the body 1. This device is adapted to effect the operation of either of the pistons 15 or 17, (in this case the piston 17), in the event that both pistons 15 and 17 are on dead-center. This dead-centering would cut off the connections of lines I and O and lines 53 and 55 with the inlet 301, thus shutting off all outlets for the supply line 301. The pressure therein would then build up until the limit of capacity of the pump be reached. Operation would then cease; and although this is a contingency effective only under certain conditions, a method of overcoming it is described hereinafter in order that all applications of the invention to different conditions may be made clear.

Referring therefore to Fig. 4 there is shown at numeral 172 an opening or passage adapted to slidably receive a plunger 171. The right-hand end 163 of the opening 172, is enlarged at 173 to accommodate a spring 187 which reacts against a shoulder 189 formed on a rod 167, cooperating with the plunger 171, to hold the plunger in its normal position. A head 165 forms the other seat for the spring 187. A resilient plug 169 is positioned between the rod and the plunger to prevent the leakage of fluid from the opening 172 to the larger part 173.

The opening 172 is in constant communication with the inlet passage 9 by way of the bore 177. The bore 177 enters the opening 172 below the plunger 171. A passage 179 connects the opening 172 with the passage 53 when the plunger 171

is up. Passages 181 and 182 enter the opening 172 at the same axial location and are shut off from communication with each other when the plunger 171 is in the normal position shown. Passage 181 connects the opening 172 with the 5 passage 55. Passage 182 connects the opening 172 with the exhaust bore 303. The plunger 171 is also adapted to close the communication between the passage 179 and the opening 172 when in its lowermost position. The plunger 171 has a groove 183 adapted to form a connecting port between the passages 181 and 182 when in a certain position determined by applied pressure. An extension of smaller diameter 176 is formed on the plunger for limiting the motion of the plunger 15 which would otherwise tend to shut off the bore 177 (Fig. 4). The plug 175 cooperates with the extension to limit the movement, inasmuch as the packing 169 is only a compression link and not a tension link.

It is clear that when the plunger 171 is in its normal position (to the left, Fig. 4) the passage 179 is cut off from communication with the inlet from the passage 9, by the plunger 171. The spring 187 has sufficient strength to hold the 25 plunger from movement under the normal pressure and the pressure equal to the relief pressure which may exist in the lines I and O and in the inlet line 301.

When, however, the pistons 15 and 17 are both 30 dead-centered, the pressure in the line 301 and consequently in the bore 9 will build up to exceed that of the said normal and relief pressures. This high pressure being communicated to the left-hand side of the plunger 171, by way of the passage 177, forces the plunger to the right against the action of the spring 187 and uncovers the passage 179, thereby connecting the pressure lines 301 with the left-hand side of the piston 17, by way of the passages 9, 177, 179 and 53. At the 40 same time the groove 183 connects the passages 181 and 182, thereby allowing the right-hand end of said piston 17 to exhaust to the exhaust line 303. Thus the piston 17 is forced from dead-center to its right-hand position and the pressure 45 line 301 is immediately communicated to the line O. The piston 15 is also thrown off dead-center by the pressure communicated to its ends by the methods previously described in connection with the proper operation of the piston 17.

With the pressure relieved the plunger 171 is immediately forced back into its normal position by the action of the spring. It is thus seen that whenever a dead-centering of both the pistons 15 and 17 occurs they are automatically moved 55 from dead-center by the device described.

An advantage of the invention is that the engine necessary to operate the oscillating device in the said United States Patent 1,805,303 has been eliminated and a simplified hydraulic means 60 has been substituted which enables the entire alternating and regulating device to be combined in a single unit comprising one block.

Furthermore the dead centering difficulty 65 which is inherent with most pneumatic and hydraulic machines has been eliminated.

It is to be understood that the elements which positively prevent dead-centering (shown primarily in Fig. 4) may be eliminated where the pressure conditions and the fits between parts are such that dead-centering will not ordinarily or perhaps never occur.

It will be seen from the above that the piston 70 75 in the device A comprises movable means

adapted to direct pressure from the inlet to either of the lines I and O. This direction is selective. The function of the device B is likewise directive and selective in regard to fluid flow.

5 In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

15 I claim:

1. In apparatus of the class described, a body having an inlet and a plurality of outlets and an exhaust, a primary valve means adapted to alternately connect the inlet with an outlet and simultaneously another outlet with the exhaust, secondary valve means adapted to control said primary valve means by directing pressure thereto from said inlet and connecting means between said outlets and the secondary valve means, whereby the latter is rendered operable.

2. In apparatus of the class described, a body having an inlet and a plurality of outlets and an exhaust, a primary valve means adapted to alternately connect the inlet with the respective outlets, secondary valve means adapted to control said primary valve means by directing pressure thereto from said inlet, connecting means between said outlets and the secondary valve means, whereby the latter is rendered operable and regulating means associated with said connecting means adapted to permit operation of said secondary valve means at predetermined outlet pressures.

3. In apparatus of the class described, a body having an inlet and a plurality of outlets and an exhaust, a primary valve means adapted to alternately connect the inlet with the respective outlets, secondary valve means adapted to control said primary valve means by directing pressure thereto from said inlet, connecting means between said outlets and the secondary valve means, whereby the latter is rendered operable, regulating means associated with said connecting means adapted to permit operation of said secondary valve means at predetermined outlet pressures, which are higher than normal at the outlets and safety regulating means connected with said inlet adapted to prevent centering of the valve means under inlet pressures in excess 55 of the operating pressures for operating said valve means.

4. In apparatus of the class described a body portion having an inlet and at least two pressure outlets and an exhaust, a main pressure operated valve means located in said body portion adapted to alternate connections between the inlet and said outlets, and between said outlets and said exhaust, said body also being provided with connections between said inlet and the pressure operated portions of said valve means, a second valve means in said body interposed between said inlet and said last-named connections adapted to alternate the connections between said inlet and the pressure operated portions of said main valve means.

5. In apparatus of the class described a body portion having an inlet and at least two pressure outlets and an exhaust, a main pressure operated valve means located in said body portion adapted

to alternate connections between the inlet and said outlets, and between said outlets and said exhaust, said body also being provided with connections between said inlet and the pressure operated portions of said valve means, a second valve means in said body interposed between said inlet and said last-named connections adapted to alternate the connections between said inlet and the pressure operated portions of said main valve means and regulators in communication with said outlets, said regulators having regulated pressure outlets communicating with said second-named valve means for delivering operating pressures thereto.

6. In apparatus of the class described a body portion having an inlet and at least two pressure outlets and an exhaust, a main pressure operated valve means located in said body portion adapted to alternate connections between the inlet and said outlets, and between said outlets and said exhaust, said body also being provided with connections between said inlet and the pressure operated portions of said valve means, a second valve means in said body interposed between said inlet and said last-named connections adapted to alternate the connections between said inlet and the pressure operated portions of said main valve means and regulators in communication with said outlets, said regulators having regulated pressure outlets communicating with said second-named valve means for delivering operating pressures thereto, said regulating means being adapted to limit the pressures at said outlets.

7. In apparatus of the class described a body portion having an inlet and at least two working pressure outlets, and an exhaust, a main pressure operated valve means located in said body portion adapted to alternate the connections between the inlet and said outlets, and between said outlets and said exhaust, said body being provided with connections between said inlet and the pressure operated portions of said valve means, a second valve means interposed between said inlet and said last-named connections, adapted to alternate the connections between said inlet and the ends of said main valve means, regulators interposed between said main valve means and said outlets, said regulators being adapted to operate at pressures higher than said working pressure and adapted to transmit said higher pressure to the ends of said second-named valve means.

8. In apparatus of the class described a body portion having an inlet and at least two working pressure outlets, and an exhaust, a main pressure operated valve means located in said body portion adapted to alternate the connections between the inlet and said outlets, and between said outlets and said exhaust, said body being provided with connections between said inlet and the pressure operated portions of said valve means, a second valve means interposed between said inlet and said last-named connections, adapted to alternate the connections between said inlet and the ends of said main valve means, regulators interposed between said main valve means and said outlets, said regulators being adapted to operate at pressures higher than said working pressure and adapted to transmit said higher pressure to the ends of said second-named valve means, said regulating means being adapted to place the connections which are not in communication with the inlet into communication with the exhaust.

9. In apparatus of the class described a body portion having an inlet and at least two working pressure outlets, and an exhaust, a main pressure operated valve means located in said body portion adapted to alternate the connections between the inlet and said outlets, and between said outlets and said exhaust, said body being provided with connections between said inlet and the pressure operated portions of said valve means, 5 a second valve means interposed between said inlet and said last-named connections, adapted to alternate the connections between said inlet and the ends of said main valve means, regulators interposed between said main valve means and 10 said outlets, said regulators being adapted to operate at pressures higher than said working pressure and adapted to transmit said higher pressure to the ends of said second-named valve means, said regulating means being adapted to 15 place the connections which are not in communication with the inlet into communication with the exhaust, and adjustable means associated with said regulating means for determining the respective pressures at which the respective pairs 20 of outlets shall be in communication.

10. In apparatus of the class described a body having an inlet and at least two outlets for pressure and an exhaust, movable means in said body portion adapted to direct the pressure between said inlet and said outlets, fluid lines connecting said inlet and the ends of said movable means to operate the same, a second movable means in said body interposed between said inlet and said ends adapted to direct the connections 30 between said inlet and said ends, a safety regulator having an inlet line connected with the inlet and an outlet line connected with an end of one of the movable means and means associated with said regulator adapted to connect the opposite end of the movable means which it 35 controls to said exhaust when said regulator is operative.

11. In apparatus of the class described a body having an inlet and at least two outlets for pressure, and an exhaust, movable means in said body portion adapted to direct the pressure between said inlet and outlets, fluid lines connecting said inlet and the ends of said movable means, a second movable means interposed between said 40 inlet and said ends adapted to direct the connections between said inlet and said ends, a safety regulator having an inlet line connected with the inlet of said body portion and an outlet line connected with an end of one of said movable means and means associated with said safety 45 regulator adapted to provide a fluid connection with said exhaust, regulating means interposed between said first-named movable means and said outlet, said regulating means having outlets connected with the ends of said second-named movable means and adapted to operate at another pressure, said safety regulator being adapted to 50 operate at a pressure higher than said other pressures.

12. In apparatus of the class described, a body portion having an inlet, a plurality of outlets and an exhaust, reciprocable means in the body comprising two members, a main one of which is adapted to selectively deliver pressure from the inlet to one of said outlets while the other outlet is connected to said exhaust, the other reciprocable member being adapted to effect direction of pressure, means adapted to cause said last-named direction of pressure to effect reciproca- 55 tion of said main member, said other reciprocable

cable member being adapted to be reciprocated by pressures effected at said outlet from the body.

13. In apparatus of the class described, a body portion having an inlet, a plurality of outlets and an exhaust, reciprocable means in the body comprising two members, a main one of which is adapted to selectively deliver pressure from the inlet to one of said outlets while the other outlet is connected to said exhaust, the other reciprocable member being adapted to effect direction of pressure, means adapted to cause said last-named direction of pressure to effect reciprocation of said main member, said other reciprocable member being adapted to be reciprocated by 10 pressures effected at said outlets from the body, and regulating means interposed between said outlets and said other reciprocable member adapted to regulate the pressures at which said other reciprocable member shall change the pressure 15 applied to said main member.

14. In apparatus of the class described, a body portion having an inlet, a plurality of outlets and an exhaust, reciprocable means in the body comprising two members, a main one of which is 20 adapted to selectively deliver pressure from the inlet to one of said outlets while the other outlet is connected to said exhaust, the other reciprocable member being adapted to effect direction of pressure, means adapted to cause said 25 last-named direction of pressure to effect reciprocation of said main member, said other reciprocable member being adapted to be reciprocated by pressures effected at said outlets from the body and means for preventing dead centering 30 of said reciprocable means.

15. In apparatus of the class described, a body portion having an inlet, a plurality of outlets and an exhaust, reciprocable means in the body comprising two members, a main one of which is 35 adapted to selectively deliver pressures from the inlet to one of said outlets while the other outlet is connected to said exhaust, the other reciprocable member being adapted to effect direction of pressure, means adapted to cause said 40 last-named direction of pressure to effect reciprocation of said main member, said other reciprocable member being adapted to be reciprocated by pressures effected at said outlets from the body and means for preventing dead centering 45 of said reciprocable means.

16. In apparatus of the class described, a body portion having an inlet, a plurality of outlets and an exhaust, reciprocable means in the body comprising two members, a main one of which is 50 adapted to selectively deliver pressure from the inlet to one of said outlets while the other outlet is connected to said exhaust, the other reciprocable member being adapted to effect direction of pressure, means adapted to cause said last-named direction of pressure to effect reciprocation of said main member, said other reciprocable member being adapted to be reciprocated by 55 pressures effected at said outlets from the body, means for preventing dead centering of said reciprocable means, said means for preventing dead centering comprising a regulator in communication with said inlet adapted to be moved by pressure at said inlet and to effect movement 70 of said reciprocable means.

17. In apparatus of the class described, a body portion having an inlet, a plurality of outlets and an exhaust reciprocable means in the body comprising two members, a main one of which is adapted to selectively deliver pressure from the inlet to one of said outlets, while the other outlet is connected to said exhaust, the other reciprocable member being adapted to effect direction of pressure, means adapted to cause said last-named reciprocation of said main member, said other reciprocable member being adapted to be reciprocated by pressures effected at said outlets from the body, regulating means interposed between said outlets and said other reciprocable member adapted to regulate the pressures at which said other reciprocable member shall change the pressure applied to said main member, and means for preventing dead centering of said reciprocable members, said means for preventing dead centering comprising another regulator in communication with said inlet adapted to be moved by excess pressure at said inlet and to effect movement of said reciprocable means.
18. A self-reversing valve comprising a body having a pressure inlet and a pair of outlets, a slidable member in said body adapted to connect said inlet selectively to said outlets, said body having a pair of passages leading from said inlet to opposite sides of said member, said body having also a pair of return ports, a pilot member 5 slidably mounted in said body between said ports and operable by differential pressure therein, said pilot member being adapted to selectively obstruct said passages, whereby to govern the movement of said first named member. 10
19. A self-reversing valve comprising a body having a pressure inlet and a pair of outlets, a slidable member in said body adapted to connect said inlet selectively to said outlets, said body having a pair of passages leading from said inlet to opposite sides of said member, said body having also a pair of return ports, a pilot member 15 slidably mounted in said body between said ports and operable by differential pressure therein, said pilot member being adapted to selectively obstruct said passages, whereby to govern the movement of said first named member, and relief lines extending from said body to prevent trapping of fluid therein. 20
25. 18. A self-reversing valve comprising a body having a pressure inlet and a pair of outlets, a slidable member in said body adapted to connect said inlet selectively to said outlets, said body having a pair of passages leading from said inlet to opposite sides of said member, said body having also a pair of return ports, a pilot member 25 slidably mounted in said body between said ports and operable by differential pressure therein, said pilot member being adapted to selectively obstruct said passages, whereby to govern the movement of said first named member.

LUTWIN C. ROTTER.
